UNITED STATES PATENT OFFICE.

EDMUND H. WALKER, OF NEW YORK, N. Y.

DRAFT GEAR.

Application filed May 2, 1923. Serial No. 636,057.

To all whom it may concern:

Be it known that I, EDMUND H. WALKER, a citizen of the United States, residing at New York, in the county of New York and State of New York, have invented certain new and useful Improvements in Draft Gears, of which the following is a specification.

My invention relates to friction draft gear and, particularly stated, involves the production of a strong, durable and efficient spring barrel which can be economically manufactured.

One of the principal features of the invention is to produce a spring barrel in which means is provided for preventing the incorrect assembly of the associated parts and especially the friction head or box, said means involving a projection disposed externally of the barrel adjacent one end thereof.

Another object of the invention is to provide a spring barrel with projections, which projections in addition to serving the aforesaid purpose of preventing incorrect assembly, also act as guide means in centering the gear between the car sills.

A still further object of the invention is to cast a spring barrel with integral means arranged to prevent the assembly of the friction box except upon but one end of the barrel, the provision of this means contributing to a material reduction in the cost of manufacture of the barrel in that but one end of the casting is required to be faced off or finished to receive said friction box.

The invention further consists in the arrangement and combination of the parts hereinafter described.

In the drawings illustrating two embodiments of my invention, the scope whereof is pointed out in the claims:

Figure 1 is a plan view illustrating an embodiment of my invention associated with friction shock absorbing devices included within a railway draft rigging of the Farlow type.

Figure 2 is a similar view showing my improved spring barrel in associated relation to a railway draft rigging including a vertical yoke, front and rear followers, and co-acting front and rear stop members.

Figure 3 is a detail end view of the barrel employed in the construction shown in Figure 1.

Figure 4 is a detached view in vertical

longitudinal section of the barrel shown in Figure 1.

Figure 5 is an end view of the barrel shown in Figure 2.

Referring to the drawings wherein similar reference characters designate corresponding parts in the several views, there is shown in Figure 1 a railway draft rigging including center sills or draft sills 1, each of said sills being provided with a cheek plate 2, said sills and cheek plates being suitably slotted to permit the relative movement of the keys in the usual manner. Positioned between the sills is the horizontal yoke 3, the forward ends of the yoke arms being slotted to receive the front key (not shown) which connects the coupler 4 with said yoke and extends into the aligned slots in the sills and cheek plates, as will be understood. The rear key 5 extends through the second series of slots in the sills and cheek plates, said second named key also passing through slots provided in the yoke arms and the follower block 6 interposed between the butt of the coupler and the friction device. A rear stop member or backstop 7 is provided with which the rear of the yoke contacts.

The friction device shown is of the Sessions type and comprises a friction head or box 8 having contained therein a plurality of friction elements indicated generally by the numeral 9. The friction head may be of the usual construction and is provided with rearwardly extending projections 10 adapted to engage the forward end of my improved barrel 11 with which the friction head contacts and in which is contained the cushioning device of the car.

The spring barrel or casing 11 used in the Farlow arrangement of draft gear is shown detached in Figures 3 and 4, and comprises a plurality of side wall portions disposed to form an octagonally shaped barrel in transverse section. The barrel may be of other shapes and is open at both ends to provide a sleeve-like structure, the cross sectional area and arrangement of the walls being substantially uniform throughout its length. It is this simplicity and attending similarity of the opposite ends of the barrel which necessitates the provision of means designed to insure the correct assembly of the barrel with the other parts of the friction gear.

Some of the side wall portions of the barrel are preferably increased in thickness or

cross sectional area, said portions being shown herein as the top and bottom walls of the casing when in its position within the draft rigging. The diagonal side wall portions adjacent said respective top and bottom wall portions are formed of slightly less cross sectional area, as shown, and the opposite vertically arranged side wall portions of the barrel are preferably formed of even 10 less cross sectional area than said diagonal side wall portions. The relative disposition of the metal in the side wall portions provides an effective column area of great strength at points subjected to the greatest 15 strains.

The barrel is provided at the rear end thereof with projections 12, said projections being formed integral at the top and bottom side wall portions of the barrel and 20 being spaced from the extreme rear end thereof. These projections or lugs are arranged upon the outside of the barrel and are disposed so as to intercept any attempted 25 application of the friction box or head to this end of the barrel. I have shown a single lug upon the top and bottom wall portions, the same being preferably centrally located and of a height sufficient to arrest the attempted fitting of the friction head upon 30 this end of the barrel. In the Farlow arrangement of draft rigging the lugs may be formed relatively small and are disposed vertically between the center sills. The lugs are also preferably set back from the extreme 35 ends of the barrel so as to permit the barrel or adjacent draft rigging part to rock or angle without imparting to the lugs the strains incident to such movements.

In Figure 2 another embodiment and arrangement of my invention is illustrated. 40 The barrel 11 is formed of side wall portions similarly disposed to those shown in Figure 3 and adapted to produce the octagonally shaped casing shown in Figure 5. The barrel is associated with a friction head or box 13, the friction elements being indicated by the numeral 14. Projecting portions 15 extend from the friction head and embrace the side wall portions of the barrel, 45 as shown.

The draft rigging in which this second embodiment of my invention is incorporated includes the draft sills or center sills 1-1 to which are connected front stop members 16 and rear stop member 17. A yoke 18 of the 50 vertical type is arranged between the car sills and is adapted to be connected to the coupler in an approved manner. Interposed between the front and unfinished end of the 55 barrel casting and the front stop member 16, is the front follower block 19. The rear follower block 20 is arranged between the friction elements 14 and the rear stop members and rear end of the yoke.

60 In the form of draft rigging shown in

Figure 2, the barrel is provided with projecting members 21 formed of a size which will permit them to act as guide members capable of contacting the inner faces of the sills and maintain the barrel and associated 70 cushioning mechanism in central position between said sills. By comparison with the Farlow arrangement of draft rigging and spring barrel, the barrel shown in Figures 75 2 and 5 is disposed horizontally with the extensions or lugs 21 projecting laterally toward the sills and spaced therefrom with sufficient clearance to permit the proper functioning of the shock absorbing mechanism under service conditions. The projections 80 21 are formed integral with the thickened side wall portions of the barrel, said thickened portions serving to provide a maximum column area adjacent to and paralleling the sills. As shown in Figure 2, the 85 projections 21 overlie the front and rear stop members, but are sufficiently set back from the extreme front end of the barrel to prevent rocking or angling movement of either the barrel or front follower contacting and injuring the lugs. The projections 21 are formed of a size sufficiently large to permit them to perform the functions of guiding and maintaining the cushioning mechanism centrally of the sills. 90 95

A cast steel spring barrel constructed in accordance with my present invention can be interchangeably used in different arrangements of draft rigging and at the same time maintain the relative strength 100 throughout the column area of the barrel, the provision of means externally of the barrel for accomplishing the purposes set forth contributing to an economic manufacture thereof and a substantial saving 105 over the improper assembly of the parts as heretofore experienced.

I claim:

1. A spring barrel for friction draft gear having opposite open end portions of substantially similar contour, and means arranged externally of said barrel adjacent one end thereof for preventing the incorrect assembly of the friction head thereto. 110

2. A spring barrel for friction draft gear having opposite open ends, and means adjacent at least one of said ends and extending from the outer surface of the barrel for intercepting the application of a friction box to said end but permitting its attachment to the other end of said barrel. 115 120

3. A spring barrel for friction draft gear having opposite open end portions of substantially similar contour, and a projection arranged to extend beyond the outer surface 125 of the barrel, said projection being located relatively close to one end face of the barrel and adapted to prevent the application of a friction box to said end but permitting its application to the other end of said barrel. 130

4. A cast steel spring barrel for friction draft gear involving a plurality of wall sections integrally united to form a sleeve-like structure having opposite open ends, and a member formed integrally with at least one of said wall sections for preventing the assembly of a friction head to one end of the sleeve but permitting its attachment to the other end thereof.
5. A cast steel spring barrel for friction draft gear comprising a series of variously thickened wall portions forming varying cross sectional column areas throughout the length of the barrel, and means formed integrally with the thicker part of said wall portions and adapted to extend beyond the outer surface of the barrel, said means acting to prevent the incorrect assembly of a friction head to one end of the barrel but permitting its application to the opposite end of said barrel.
6. A spring barrel for friction draft gear having opposite open end portions, and means carried by said barrel and projecting beyond the outer surface upon opposite sides of the barrel, said means acting to guide and maintain the barrel centrally of the car sills and also acting to prevent the incorrect assembly of the friction head to one end of the barrel but permitting its application to the opposite end thereof.
7. A cast steel spring barrel for friction draft gear comprising a series of variously thickened wall portions forming varying cross sectional column areas throughout the length of the barrel, and projections formed integrally with the thicker part of opposite wall portions, said projections forming a
- guiding means for the barrel when in the draft rigging assembly and also acting to prevent the application of a friction box to one end of the barrel but permitting its application to the opposite end thereof.
8. In a draft rigging, the combination with center sills, of a coupler and yoke, a shock absorbing mechanism involving a friction device and spring barrel, and means carried by said barrel and projecting beyond the outer surface upon opposite sides of the barrel, said means being adapted to guide and maintain the cushioning mechanism centrally of the sills and also being located adjacent one end of the barrel for preventing incorrect assembly of the associated parts of said shock absorbing mechanism.
9. In a draft rigging, the combination with center sills, of a coupler and yoke front and rear stop members connected to each of said sills, a shock absorbing mechanism involving a friction device and barrel, said barrel having relatively thickened portions extending throughout the length thereof and adjacent the center sills, and means formed integral with said barrel and projecting from said thickened portions, said means being adapted to overlie the stop members for guiding the cushioning mechanism and also being located on said barrel to prevent the incorrect assembly of a friction box upon one end of the barrel but permitting its application to the other end thereof.

In testimony whereof I affix my signature.

EDMUND H. WALKER.
